UNITED STATES PATENT OFFICE.

CALEB WEIR, OF MALVERN, PENNSYLVANIA.

THILL-COUPING.

SPECIFICATION forming part of Letters Patent No. 395,021, dated December 25, 1888.

Application filed October 2, 1888. Serial No. 287,010. (No model.)

To all whom it may concern:

Be it known that I, CALEB WEIR, a citizen of the United States, residing at Malvern, in the county of Chester, State of Pennsylvania, have invented a new and useful Improvement 5 in Thill-Couplings, which improvement is fully set forth in the following specification and accompanying drawings.

My invention relates to improvements in 10 thill-couplings, the object being to provide a thill-coupling which can be easily applied, which will securely retain the thills in place and prevent rattling of the same, and which will permit of the easy removal of the thills 15 when desired.

To attain the desired object, the invention consists of a thill-iron having lugs or studs, and a draw-iron having ears provided with 20 sockets to receive said studs, one of the ears of the draw-iron being movable to allow the attachment and detachment of the thill-iron.

It further consists in a thill-iron, a draw-iron having a hinged ear, a clip capable of moving or sliding to allow the movable ear to be opened 25 in order to release the thill-iron, and an eccentric bearing against the axle for drawing the thill-iron in and preventing the opening of the ear, thereby securing the thill in place.

Figure 1 represents a top plan view, partly 30 broken away, of a thill-coupling embodying my invention. Fig. 2 represents a vertical longitudinal section thereof. Fig. 3 represents a horizontal section thereof, the parts being opened.

Similar letters of reference denote corresponding parts in the several figures.

Referring to the drawings, A designates the thill-iron, whose ear is provided with laterally-extending studs B for attaching the thill-iron in place and forming the journals thereof.

C designates the draw-iron having the ears D and E, provided with sockets or depressions F to receive the journals B of the thill-irons and forming bearings for said journals. The 45 ear E is hinged at its rear end to the draw-iron, so as to move laterally and thus open and close.

G designates plates secured to the rear of the draw-iron, and freely embracing the axle 50 and connected therewith, thus permitting sliding movement of the draw-iron, the purpose

of which is to allow the turning of the ear to relieve the thill-iron and to secure said iron in position by causing the rear of the hinged ear as a shoulder to abut against the axle and prevent the turning of said ear when the clip is moved in. 55

H designates an eccentric pivoted between the plates G, and adapted to bear against the back of the axle for moving the draw-iron, 60 said eccentric being provided with a lever or arm, J, adapted to be engaged by a spring or other catch, K, for holding it in position.

The operation is as follows: When it is desired to secure the thill-iron to the draw-iron, 65 the eccentric is rotated to release its pressure on the axle, and the draw-iron is moved forward. The hinged ear is now turned, allowing the thill-iron to be placed between the ears of the draw-iron, after which said ear is 70 shut, thus confining the thill-iron within the draw-iron. The eccentric is rotated, thus sliding the draw-iron rearward and causing the heel or shoulder of the ear E to abut against the axle and prevent said ear from opening, 75 thus securely holding the thill-iron in place. To remove the thill, it is merely necessary to operate the eccentric in reversed direction, move the draw-iron forward, and open the hinged ear, whereby the thill-iron is released 80 and may be withdrawn, as is evident.

It is evident that the plates G G may be made in one piece with the draw-iron D, or separately, and secured thereto, as above stated. 85

Having thus described my invention, what I claim as new, and desire to secure by Letters Patent, is—

1. A thill-coupling consisting of the draw-iron having the stationary and movable or 90 hinged ear, the draw-iron plates freely embracing the axle, and an eccentric pivoted to said plates and adapted to bear against the axle and bring the heel of the hinged ear in contact with the axle and prevent said ear 95 from being opened, substantially in the manner and for the purpose described.

2. A thill-coupling consisting of a draw-iron having a stationary and movable ear, a 100 clip carried by the draw-iron and freely embracing the axle in order to have a sliding movement on said axle, and devices for mak-

ing the movable jaw stationary and securing the draw-iron in place, substantially as and for the purpose described.

3. In a thill-coupling, the combination, with the thill-iron, of the draw-iron having stationary and movable ears, sliding plates carried by said ears freely embracing the axle and permitting sliding movements of the draw-iron, and an eccentric pivoted to said plates and adapted to engage the axle to prevent the movement of the draw-iron, substantially in the manner and for the purpose described.

4. In a thill-coupling, the draw-iron having a hinged ear, and plates carrying the same freely embracing the axle and permitting sliding movements of said draw-iron, and an eccentric or cam adapted to move the draw-iron inward to cause the hinged ear thereof to abut against the axle as a stop, substantially in the manner and for the purpose described.

5. A thill-coupling consisting of a draw-iron capable of sliding movement on the axle, and a cam or eccentric for holding said draw-iron in place on the axle, substantially as and for the purpose described.

6. In a thill-coupling, a draw-iron provided with ears, one stationary and the other movable, and made capable of a sliding movement on the axle to allow the opening of said movable ear, and a cam or eccentric for retaining the said draw-iron in place and securing the movable jaw in closed position, substantially in the manner and for the purpose described.
